RESISTANCE-CARRYING BODY FOR RHEOSTATS AND THE LIKE

Peter H. Voorlas, Racine, Wis.

Application January 27, 1949, Serial No. 526

Term of patent 14 years

(Cl. D26—1)

To all whom it may concern:

Be it known that I, Peter H. Voorlas, a citizen of the United States, residing at Racine, county of Racine, State of Wisconsin, have invented a new, original, and ornamental Design for a Resistance-Carrying Body for Rheostats and the like, of which the following is a description, reference being had to the accompanying drawings, forming a part thereof.

Fig. 1 is a top plan view of my resistance-carrying body for rheostats and the like;

Fig. 2 is a bottom plan view of the body shown in Fig. 1; and

Fig. 3 is a front elevational view of said body in inverted position as shown in Figure 2.

I claim:

The ornamental design for a resistance-carrying body for rheostats and the like, substantially as shown.

PETER H. VOORLAS.
